DRILLING APPARATUS

Morris P. Holmes, Claremont, N. H., assignor to
 Sullivan Machinery Company, a corporation of
 Massachusetts

Application November 16, 1928, Serial No. 319,922

54 Claims. (Cl. 255—51)

This invention relates to drilling apparatus and more particularly to a drilling apparatus of the self-propelled type especially adapted to use in drilling coal or similar materials in mines and adapted to operate from the mine trackway.

An object of this invention is to provide an improved drilling apparatus especially adapted to use in coal or similar mines whereby a plurality of "shot" holes may be simultaneously drilled in the working face. Another object of this invention is to provide an improved drilling apparatus having improved tool adjusting, supporting, and driving means, whereby the tool may be quickly adjusted relative to the working face and fed relative to the work in an improved manner. Another object is to provide an improved drilling apparatus of the wheel mounted self-propelled type wherein but a single driving motor is utilized in propelling the apparatus along the trackway, adjusting the tool supporting means, and for driving the tool rotating and feeding means, and which lends itself to use with one or more tools. Still another object is to provide an improved drilling apparatus of the multiple tool type wherein improved and simplified power operated mechanism is employed for independently adjusting the tool supports whereby the tools may be independently positioned relative to the work. Yet another object is to provide an improved truck mounted self-propelled drilling apparatus of the multiple tool type which may be quickly transported from place to place and set up with facility, thereby materially decreasing the time consumed with the resultant decrease in labor cost. Another object is to provide an improved coal drilling apparatus of the multiple tool type having improved adjustable supporting means for the drilling tools whereby the latter may be positioned relative to the coal face close to and parallel with the roof and mine bottom and the ribs of the coal. These and other objects of this invention will, however, subsequently more fully appear as the description proceeds.

In the accompanying drawings there is shown for purposes of illustration one form which the invention may assume in practice.

In these drawings.—

Fig. 1 is a plan view of the improved drilling apparatus, the drilling tools being shown adjusted into a plurality of lateral positions.

Fig. 2 is a side elevational view of the drilling apparatus shown in Fig. 1, the drilling tools being shown in a plurality of vertically adjusted positions.

Fig. 3 is a central longitudinal vertical sectional view through one of the drilling tools, per se, the view being taken substantially on line 3—3 of Fig. 1.

Fig. 4 is a transverse horizontal sectional view taken substantially on line 4—4 of Fig. 2.

Fig. 5 is a vertical sectional view taken substantially on line 5—5 of Fig. 1.

Fig. 6 is a transverse vertical sectional view taken substantially on line 6—6 of Fig. 5.

Fig. 7 is a detail view illustrating the operating means for the reverse clutch mechanism.

Fig. 8 is a detail sectional view illustrating one of the locking devices for the tool supporting turntables.

While the features of my invention are in the main equally applicable to a single drill mechanism, in the illustrative embodiment of the invention there is shown a drilling apparatus of the wheel mounted, self-propelled, multiple spindle or multiple tool type generally comprising a wheeled truck 1 on which are supported drilling tools 2 and 3, by means of improved adjustable supporting means generally designated 4 for each tool. As shown, the wheeled truck 1 comprises a truck frame or body 5 mounted on wheels 6 adapted to run along a trackway 7. The wheels 6 are herein secured to front and rear axles 8 and 9 journaled in suitable axle boxes carried by the truck body. Rigidly mounted upon the truck body 5 at its forward end is a frame or housing 10 in which certain transmission elements of the truck wheel driving and tool adjusting, driving and feeding means are housed, as will later be described. Supported on this frame or housing 10 is a vertical motor 11, herein preferably of the reversible electric type, having fixed to the lower end of its armature shaft 12 a motor pinion 13 projecting downwardly within the housing 10. Meshing with this motor pinion is a spur gear 14 keyed at 15 to a vertical shaft 16 suitably journaled within the frame 10.

The improved truck wheel driving mechanism herein comprises a bevel pinion 17 herein formed integral with the lower end of the shaft 16 and meshing with oppositely rotating reverse bevels 18 and 19. These bevel gears 18 and 19, as shown in Fig. 6, are journaled on a transverse horizontal shaft 20, in turn journaled within the housing 10. Keyed to the opposite ends of this shaft 20 at opposite sides of the truck body are chain sprockets 21 and 22 respectively, the sprocket 21 being connected by a chain and sprocket connection 23 to the rear axle 9, while the sprocket

22 is connected to the front axle 8 by a chain and sprocket connection 24. As shown in Fig. 6 the bevel gear 18 carries a series of friction plates 25 interleaved with similar friction plates 5 26 carried by a clutch member 27 keyed at 28 to the shaft 20. Similar friction plates 29 and 30 are carried respectively by the bevel gear 19 and a clutch member 31 also keyed to the shaft 20. The friction clutches within the bevel gears 18 10 and 19 are adapted to be alternatively applied to connect one or the other of the bevel gears to the shaft to thereby effect drive of the latter in opposite directions by means of a clutch applying member 32 slidably mounted for endwise movement on the adjacent hubs of the bevel gears 18 15 and 19. Engaging this clutch applying member is a shipper member 33 fixed to a transverse operating rod 34 slidably mounted within the frame 10. This clutch operating rod is adapted to be 20 shifted axially by a suitable operating lever 35 pivotally mounted on the frame 10 at one side of the truck (see Fig. 1).

The mechanism for driving the tool rotating and feeding mechanism herein comprises spur 25 gears 36 and 37 having their axes lying in the same vertical transverse plane and spaced equally from the longitudinal center of the apparatus. The gear 36 herein drives the feeding and rotat- 30 ing means of the drilling tool 2 while the gear 37 drives the rotating and feeding means of the drilling tool 3. As the driving connections between the gears 36 and 37 and the rotating and feeding means of the drilling tools 2 and 3 are identical, it is thought that a description of the 35 driving connections for one will suffice for both. As shown in Fig. 5 the spur gear 36 is keyed at 38 to the lower end of a vertical shaft 40 journaled in suitable bearings carried by a swivel frame or housing 41. It will herein be noted that 40 the swivel frame 41 has secured thereto by means of screws 42 an annular bearing member 43 rotatably mounted within bearing sleeves 44. These bearing sleeves 44 are supported by the 45 frame 10 and are held in position by an annular retaining ring 45 bolted to the frame 10. It will therefore be evident that the swivel frame, together with its bearing structure, forms a horizontal turntable mounted on the frame 10 for rotation about a vertical axis and supporting the 50 drilling tool 2. Again referring to the tool rotating and feeding mechanism, it will be observed that the vertical shaft 40 has keyed thereto at its upper end a bevel pinion 46 meshing with a bevel gear 47 (see also Fig. 4) journaled on a trans- 55 verse horizontal stud 48. As shown the stud 48 is keyed at 49 to the hub portion of a swingable housing or frame 50 mounted for rocking movement about a transverse horizontal axis within roller bearings 51 supported within the opposite 60 sides of the swivel frame 41. The tilttable frame 50 has a cylindrical external bearing surface 52 which engages the inner periphery 53 of the swivel housing and these surfaces cooperate to form an additional bearing for the frame 50 dur- 65 ing its rocking movement. The forward portion of the swivel frame 41 is cut away at 54 and a portion of the frame 55 of the frame 50 projects laterally through the opening formed by this cut away portion. Again referring to Fig. 5 it will 70 be noted that the bevel gear 47 meshes with reverse bevels 56 and 57. The bevel gears 56 and 57 are keyed to clutch housings 58 and 58^a respectively. The clutch housing 58 carries a series of friction plates 59 interleaved with a 75 series of similar plates 60 carried by a shaft 61.

The shaft 61 is journaled at its opposite ends within suitable ball bearings carried by the swingable housing 50. Similar friction plates 62, 63 are carried by the clutch housing 58^a and the shaft 61 respectively. The operating mechanism for alternatively applying the clutches within the clutch housings 58 and 58^a to thereby connect one or the other of the reverse bevels 56, 57 to the shaft 61 herein comprises a clutch applying member 64 surrounding and axially movable relative to the shaft 61. Engaging this clutch applying member 64 is a clutch shipper member 65 (see Fig. 7) pivotally mounted at one end as at 66 within slotted bearings formed on the inner end of the stud 48 (see also Fig. 4). As illustrated, the shipper member 65 is at its other end vertically slotted at 67 and engaging this slot is an eccentric member or crank pin 68 carried on a shaft 69 rotatably mounted within and extending axially through one of the hub portions of the swinging frame 50. Rotatably mounted on the outer end of this shaft 69 is a lever 70 for yieldingly loading the clutches and having suitable spring pressed locking means 71 for maintaining the lever in its different adjusted positions. It will thus be seen that when the lever 70 is swung in one direction or the other the eccentric pin 68 moves within the slot 67 and as a result the shipper member 65 is swung about its pivot thereby moving the clutch applying member 64 axially in one direction or the other to connect one or the other of the reverse bevels 56, 57 to the shaft 61. It will thus be evident that the shaft 61 may be driven in one direction or the other at will, the clutches being yieldably loaded in each case.

As shown in Figs. 4 and 5, the shaft 61 has keyed thereto at 72 a spur pinion 73 which drives the adjusting mechanism for the drill supporting means 4 as will later be described. Alined 40 with the shaft 61 and also keyed to the pinion 73 is a main transmission shaft 74. This transmission shaft 74 is arranged concentrically within and extends through a forwardly projecting tubular supporting arm or boom 75 mounted for rotation about its longitudinal axis within bearing sleeves 76 carried respectively by a frame 77 bolted to the laterally projecting portion 55 of the swinging frame 50, and a frame 78 fixed to the outer end of the frame 77. As shown in Fig. 50 3 the tubular supporting arm or boom 75 has secured thereto by screws 79 at its outer end a swivel frame or bearing bracket 80. The drilling tools are swiveled on the bearing brackets 80 as will later be described. In this instance the 55 outer end of the main drive shaft 74 has keyed thereto a bevel pinion 81 meshing with a larger bevel ring gear 82. The bevel ring gear 82 is rotatable about an axis perpendicular to the axis of the drive shaft 74 and is journaled on a ball bearing 83 suitably supported by a bearing bracket 84 and a swivel plate 85. This swivel plate 85 is rigidly secured by screws 86 to the bearing bracket 84 and is herein rotatably mounted in a bore 87 arranged concentrically 60 with the bevel gear 82 and formed within the bracket 80. The swivel plate 85 is provided with a peripheral groove 88 with which a clamp or set screw 89 is engageable to clamp the swivel plate together with the drilling tool in its different adjusted positions rigidly to the bracket 80. As illustrated, the bevel ring gear 82 meshes with a bevel gear 90 fixed to a shaft 91 in a plane with the main driving shaft 74. The shaft 91 is journaled in ball bearings 92 carried by the bearing 65 70 75

bracket 84. Also fixed to the shaft 91 is a spur gear 93, while formed integral with the opposite end of the shaft 91 is a spur gear 94. The gears 93 and 94 mesh respectively with spur gears 95 and 96, the spur gears 95 and 96 herein constituting the driving elements for the tool rotating and feeding mechanism. These driving elements are adapted to effect rotation and feeding of a drill bit or cutting tool 97 through friction clutches 98 and 99 and a differential screw mechanism 100. As this specific feeding and rotation mechanism for the cutting bit 97 is clearly described in my copending applications Ser. No. 200,826, filed June 23, 1927, and Ser. No. 255,754, filed February 20, 1928 now matured into Patent No. 1,933,589, patented Nov. 7, 1933, and in a copending application to one Richard E. Murphy, Ser. No. 274,821, filed May 3, 1928 now matured into Patent No. 1,848,376, patented March 8, 1932, further description of the same is herein believed to be unnecessary other than to state that the drill bit is adapted to be fed forwardly at a slow cutting speed and retracted at a relatively high speed while the same is constantly rapidly rotated, fast forward feed for positioning or slow reverse feed being possible by reversing rotation of the shaft 74. From the foregoing description it is evident that the drilling tools 2 and 3 may be swiveled on the outer ends of the supporting arms 75 and rigidly locked in any of their adjusted positions.

The mechanism for effecting rotation of the boom or tubular supporting arm 75 within its bearings 76 carried by the frame elements 55, 77, 78 herein comprises a worm gear 101 keyed at 101^a to the supporting arm 75 intermediate its supporting bearings. As illustrated meshing with the worm gear 101 is a worm 102 herein formed integral with a transverse horizontal shaft 103. This shaft carries at one end a suitable operating handle 104. This rotation mechanism for the supporting boom is clearly described in my copending applications mentioned above. It is accordingly evident that the supporting arm or boom, upon rotation of the worm gearing 101, 102, may be rotated about its longitudinal axis relative to the swingable housing 50 and as a result the drilling tool 2 may be swung bodily about the axis of the supporting arm. As this worm gearing is of the self-locking type the boom is rigidly locked against rotation after such adjustment.

The improved power operated mechanism for effecting swinging movement of the supporting means 4 together with the drilling tool supported thereby upwardly and downwardly by power herein comprises a spur gear 105 (see Fig. 5) meshing with the spur pinion 73 fixed to the shafts 61, 74 as heretofore described. This spur gear 105 is slidably mounted for axial movement on a sleeve 106 keyed at 107 to a screw threaded shaft 108. The gear 105 carries clutch teeth 109 which are engageable with clutch teeth 110 carried on the sleeve 106. The gear 105 is adapted to be shifted axially to move the clutch teeth into interlocking engagement by means of a pivoted shifter member 111 secured to an operating rod 112. This operating rod is rotatably mounted within the frame portion 55 and has fixed thereto at one end a suitable operating lever 113. Slidably mounted within parallel guideways 114 within the frame 77 is a trunnion block 115 herein in the form of a nut having internal threads 116 engaging the threads of the screw threaded shaft 108. Pivottally connected at 117 to the trunnion

block 115 are parallel link members 118 in turn pivotally connected at 119 to the upper part of the swivel housing 41. From the foregoing description it will be evident that when one or the other of the clutches 59, 60 or 62, 63 is applied and when the clutch teeth 109, 110 are connected, the screw threaded shaft 108 may be rotated in one direction or the other, thereby moving the trunnion block 115 within its guideways and swinging the supporting arm or boom, together with the drilling tool supported thereby, into different elevations, the rocking frame 50 moving within its bearings relative to the swivel frame 41 at that time. It will thus be seen that either of the drilling tools 2 and 3 may be swung upwardly or downwardly by power as desired.

Locking devices, as shown in Fig. 8, are employed for maintaining the turntables 41 on which the drilling tools are mounted in their different angular positions relative to the frame 10. These devices herein each comprises a set screw 120 threadedly connected to an upstanding bracket 121 formed on the frame 10 and this set screw abuts at its inner end a sliding block 122 mounted within a recess 123 in the bracket 121 and held in position by a detachable plate 124. As shown the sliding block 122 has an arcuate serrated inner surface 125 engageable with the smooth outer periphery of a circular portion 126 herein formed integral with the swivel frame 41 of the turntable. It will therefore be evident that upon suitable adjustment of the set screw 120 the sliding block 122 may be moved inwardly causing the serrations thereon to grip the periphery of the frame portion 126 thereby locking the turntable against rotation.

Electrical energy is supplied to the motor 11 through a conductor cable 127 wound upon a cable reel 128 mounted upon the truck body 5. Suitable guide devices 129 are provided for guiding the conductor cable 127. Extending from suitable terminal elements or plugs 130 at the sides of the cable reel are conductor cables 131 leading in a usual manner to the motor elements. Secured to the cable reel is a pulley 132 which is connected by an endless belt connection 133 to a driving pulley 134 secured to a transverse shaft 135 journaled on the truck body 5. This shaft 135 has fixed thereto at its outer end a chain sprocket 136 connected by a chain and sprocket connection 137 to the rear truck axle 9. It will thus be evident that as the apparatus moves along the trackway the cable reel is driven from the rear axle through chain connection 137, driving pulley 134, and belt connection 133, the cable reel automatically unwinding the conductor cable 127 as the apparatus moves forwardly along the trackway and winding up this conductor cable automatically as the apparatus moves rearwardly. Suitable electrical controlling apparatus is provided on the truck for controlling the supply of electrical energy to the motor 11, this controlling apparatus being generally designated at 138. A suitable braking device is provided for holding the truck wheels against rotation and herein comprises a brake drum 139 secured to the rear truck axle 9 and with which a contractile brake band 140 operates. The brake band 140 is provided with suitable operating means including a lever 141 pivotally mounted on the truck frame 5. A toothed segment 142 and latch 143 are employed for maintaining the lever 141 in its different adjusted positions. This brake is used to hold the truck wheels stationary during the drilling operation and to prevent too rapid movement of the

apparatus while moving along an inclined track-way.

- In the operation of the improved drilling apparatus the same is propelled under its own power 5 along the mine trackway by the motor 11 through the driving connections between the motor and the truck wheels as described above, the desired direction of movement of the apparatus along the trackway being controlled by suitable application 10 of the reverse controlling clutches 25, 26 and 29, 30. As the drilling apparatus moves forwardly along the trackway the cable reel 128 pays out the conductor cable 127 and when the apparatus moves rearwardly the conductor cable 127 is automatically wound in by the cable reel. When the drilling apparatus reaches the working face the operator applies the brake 139, 140 holding the truck wheels against rotation thereby maintaining the truck stationary. If it is desired 15 to operate the drilling tools at one side of the trackway to position the same close to the rib the operator releases the clamping devices 120, 122 and swings the turntables 41 thereby moving the supporting means 4 and the drilling tool supported thereby to one side of the truck as indicated by dotted lines in Fig. 1. If it is desired 20 to swing the drilling tools upwardly or downwardly, for instance to bring the drilling tools close to the mine bottom or roof as indicated by dotted lines in Fig. 2, the operator connects the clutch 109, 110 and upon suitable application of the friction clutches 59, 60 and 62, 63 the drilling tools may be swung upwardly or downwardly under motor control as desired. If it is desired 25 to swing the drilling tool about the axis of the supporting arm or boom 75 the operator rotates the worm gearing 101, 102 thereby rotating the supporting boom about its longitudinal axis. The worm gearing 101, 102 is self-locking and the boom is thereafter locked against rotation. When 30 desired the angle of the drilling tool relative to the supporting boom may be changed simply by releasing the clamping screw 89 and bodily swinging the drilling tool relative to the swivel bracket 35 80. When the drilling tools are suitably positioned adjacent the working face the clutches 98, 99 may be so controlled as to effect slow feeding movement of the drill bits 97 and after the holes are completed the drill bits may be retracted 40 from the face at a high speed in the manner clearly described in the copending applications 45 mentioned above. It will further be noted that the drilling tools may be swung independently to one side or the other of the truck and upwardly 50 or downwardly as desired so that a plurality of holes may be simultaneously drilled in any position, it being possible to swing the drilling tools close to and into parallel relation with the mine roof and bottom or to swing the same laterally 55 60 adjacent either rib.
- As a result of this invention an improved self-propelled multiple tool drilling apparatus is provided wherein the drilling tools are swingable into a plurality of positions relative to the working face, and by employing the improved supporting and adjusting means for the tools the latter may be moved into such positions with facility and expeditiously. It will further be noted that by employing the improved adjustable mountings 65 for the drilling tools the latter may be adjusted independently to either side of the truck or upwardly or downwardly as desired, the improved supporting means being so constructed as to permit the drilling tools to be positioned close to and 70 parallel with the mine roof and bottom or adja-

cent either rib. It will still further be noted that but a single motor is utilized for propelling the apparatus along the trackway, for swinging the drilling tools upwardly and downwardly, and for driving the tool rotating and feeding mechanism, the driving connections between the motor and the various elements being of a simple and reliable design adapted to withstand the severe service conditions encountered underground in mines. It will also be noted that the apparatus 10 is wholly self-contained and operates at all times from the mine trackway. It will also be noted that the drill supporting and adjusting and driving mechanisms and the improved truck mounting are equally applicable to single tool drills and 15 it is to be understood that my invention is not limited in its scope to multiple drill mechanisms other than as expressly set forth in certain of the appended claims. These and other uses and advantages of this invention will be clearly apparent to those skilled in the art.

While in this application there is specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by 30 Letters Patent is:

1. In a drilling apparatus, a portable support, a motor thereon, horizontal turntables mounted on said support for rotation about parallel vertical axes, a forwardly extending adjustable supporting structure mounted upon and supported by each turntable, a drilling tool mounted on the outer extremity of each supporting structure, and driving connections between said motor and said drilling tools.

2. In a drilling apparatus, a portable support, a motor thereon, horizontal turntables mounted on said support for rotation about parallel vertical axes, a forwardly extending adjustable supporting structure mounted upon and supported by each turntable, a drilling tool mounted on the outer extremity of each supporting structure, driving connections between said motor and said drilling tools, and mechanism driven by said motor for propelling said support.

3. In a drilling apparatus, a portable support, a motor thereon, horizontal turntables mounted on said support, a forwardly extending boom pivotally mounted at its rear end on each turntable, a drilling tool carried at the outer end of each boom, and driving connections between said motor and said drilling tools.

4. In a drilling apparatus, a portable support, a motor thereon, horizontal turntables mounted on said support, a forwardly extending boom pivotally mounted at its rear end on each turntable, a drilling tool pivotally mounted at the outer end of each boom, and driving connections between said motor and said drilling tools.

5. In a drilling apparatus, a portable support, 65 a motor thereon, a plurality of rotatable supports on said support at the forward end thereof, forwardly extending adjustable supports on said rotatable supports and overhanging and extending a substantial distance in advance of said portable support, a drilling tool carried at the outer end of each adjustable support in advance of said portable support, and driving connections between said motor and said drilling tools.

6. In a drilling apparatus, a portable support,

a pair of rotatable supports thereon at the front end thereof, a forwardly extending boom pivotally mounted at its rear end on each rotatable support and overhanging and extending a substantial distance in advance of said portable support, a drilling tool carried at the outer end of each boom in advance of said portable support, and a motor on said support for driving both of said drilling tools.

7. In a drilling apparatus, a portable support, 10 a pair of rotatable supports thereon, a forwardly extending boom pivotally mounted at its rear end on each rotatable support, a drilling tool carried at the outer end of each boom, a motor on said support for driving both of said drilling tools, and mechanism driven by said motor for swinging said booms about their pivots.

8. In a drilling apparatus, a portable support, 20 a pair of rotatable supports thereon, a forwardly extending boom pivotally mounted at its rear end on each rotatable support for swinging movement about a horizontal axis, said booms also being mounted on said rotatable supports for rotation about their longitudinal axes, a drilling tool carried at the outer end of each boom, and a 25 motor on said support for driving both of said drilling tools.

9. In a drilling apparatus, a portable support, 30 a pair of rotatable supports thereon, a forwardly extending boom pivotally mounted at its rear end on each rotatable support for swinging movement about a horizontal axis, said booms also being mounted on said rotatable supports for rotation about their longitudinal axes, a drilling tool carried at the outer end of each boom, mechanism 35 for rotating said booms about their longitudinal axes, and a motor on said support for driving both of said drilling tools.

10. In a drilling apparatus, a portable support, 40 a pair of rotatable supports thereon, a forwardly extending boom pivotally mounted at its rear end on each rotatable support for swinging movement about a horizontal axis, said booms also being mounted on said rotatable supports for rotation about their longitudinal axes, a drilling tool carried at the outer end of each boom, mechanism 45 for rotating said booms about their longitudinal axes, a motor on said support for driving both of said drilling tools, and mechanism driven by said motor for swinging said booms about their 50 horizontal axes.

11. In a drilling apparatus, a portable support, 55 a motor thereon, a pair of turntables on said support rotatable about parallel axes, a forwardly extending tubular boom pivotally mounted on a horizontal axis on each turntable, a drilling tool pivotally mounted on the outer end of each boom, mechanism for adjusting said booms about their axes including a motor, and mechanism driven by said motor for driving said drilling tools.

60 12. In a drilling apparatus, a portable support, a motor thereon, a pair of turntables on said support rotatable about parallel axes, a forwardly extending tubular boom pivotally mounted on a horizontal axis on each turntable, a drilling tool pivotally mounted on the outer end of each boom, mechanism for adjusting said booms about their axes including a motor, and mechanism driven by said motor for driving said drilling tools including driving connections extending through 65 said tubular booms.

13. In a drilling apparatus, a portable support, 70 a forwardly extending boom pivotally mounted at its rear end on said support for swinging movement about vertical and horizontal axes, a drilling tool carried at the outer end of said

boom, a motor, mechanism driven by said motor for driving said drilling tool including driving elements arranged with their axes alined with said boom-swing axes respectively, and mechanism driven by said motor through said driving elements for swinging said boom about one of its axes.

14. In a drilling apparatus, a self-propelled support, a pair of horizontal turntables mounted on the forward end of said support for rotation about parallel vertical axes at opposite sides of and spaced equally from the central longitudinal vertical plane of the apparatus, an elongated supporting arm pivotally mounted on each turntable for swinging movement in vertical planes extending longitudinally of said support about a horizontal axis, motor driven mechanism for swinging said arms about their axes, a drilling tool carried at the outer end of each arm, said arms being swingable as aforesaid to position the drilling tools to drill holes at different elevations in a direction parallel with the longitudinal axis of the apparatus, and motor driven mechanism for driving said drilling tools.

15. In a drilling apparatus, a self-propelled support, a pair of horizontal turntables mounted on the forward end of said support for rotation about parallel vertical axes at opposite sides of and spaced equally from the central longitudinal vertical plane of the apparatus, an elongated supporting arm pivotally mounted on each turntable for swinging movement about a horizontal axis, motor driven mechanism for swinging said arms about their axes, a drilling tool pivotally mounted at the outer end of each arm to swing relative thereto about an axis at right angles to the longitudinal axis of said arm, and motor driven mechanism for driving said drilling tools.

16. In a drilling apparatus, a self-propelled support, a pair of horizontal turntables mounted on the forward end of said support for rotation about parallel vertical axes, an elongated supporting arm pivotally mounted on each turntable for swinging movement about a horizontal axis, motor driven mechanism for swinging said arms about their axes, a drilling tool carried at the outer end of each arm, and motor driven mechanism for driving said drilling tools including a motor carried on said support, and driving connections between said motor and each drilling tool including transmission elements extending through said supporting arms.

17. In a drilling apparatus, a portable support, a pair of horizontal turntables thereon rotatable about parallel vertical axes at opposite sides of and spaced equally from the central longitudinal vertical plane of the apparatus, an elongated boom pivotally mounted on each of said turntables for swinging movement in vertical planes extending longitudinally of the apparatus about a horizontal axis, mechanism for effecting swinging movement of said booms about their axes, and a drilling tool pivotally mounted on the outer end of each boom and adjustable in aforesaid vertical direction relative to said support into positions to drill holes at different elevations in a direction extending longitudinally of the apparatus.

18. In a drilling apparatus, a portable support, a pair of horizontal turntables thereon rotatable about parallel vertical axes, an elongated boom pivotally mounted on each of said turntables for swinging movement about a horizontal axis, mechanism for effecting swinging movement of said booms about their axes including a motor, and a drilling tool pivotally mounted on the outer

- end of each boom, both said drilling tools driven by said motor.
19. In a drilling apparatus, a portable support, a motor carried thereby, a horizontal turntable on said support rotatable about a vertical axis, an elongated boom pivotally mounted on said turntable for swinging movement about a horizontal axis relative to said motor and turntable, mechanism driven by said motor for effecting swinging movement of said boom about its pivot and including driving elements arranged with their axes alined with the turntable and boom axes aforesaid, and a drilling tool pivotally mounted on the outer end of said boom.
- 15 20. In a drilling apparatus, a portable support, a motor carried thereby, a horizontal turntable on said support rotatable about a vertical axis, an elongated boom pivotally mounted at its rear end on said turntable for swinging movement about a horizontal axis, said boom also being mounted on said turntable for rotation about its longitudinal axis, mechanism driven by said motor for effecting swinging movement of said boom, mechanism for rotating said boom, a drilling tool pivotally mounted on the forward end of said boom including a cutting tool and rotating and feeding mechanism therefor, and driving connections between said tool rotating and feeding mechanism operative irrespective of the position of the drilling tool relative to said support.
21. In a drilling apparatus, a portable support, a motor thereon, an elongated supporting arm pivotally mounted at its rear end on said support for swinging movement about vertical and horizontal axes, said arm being swingable horizontally and vertically about said axes relative to said support and motor, a drilling tool adjustably mounted on the outer extremity of said arm, mechanism driven by said motor for driving said drilling tool and including driving elements arranged with their axes alined with the arm swing axes, and mechanism driven by said motor through said driving elements for swinging said arm vertically about said horizontal axis.
- 50 22. In a drilling apparatus, a wheeled truck, a motor thereon for driving the truck wheels to propel the apparatus along the trackway, an elongated supporting arm pivotally mounted at its rear end on said truck for swinging movement about angularly disposed axes, said arm being adjustable vertically and horizontally about said axes, mechanism driven by said motor for swinging said arm about one of its pivotal axes, a drilling tool adjustably mounted on the outer extremity of said arm, and driving connections between said motor and said drilling tool.
- 60 23. In a drilling apparatus, a wheeled truck, a motor thereon for driving the truck wheels to propel the apparatus along a trackway, an elongated supporting arm pivotally mounted at its rear end on said truck for swinging movement about angularly disposed axes including a horizontal pivotal axis, a drilling tool adjustably mounted on the outer extremity of said arm, mechanism driven by said motor for swinging said arm about its horizontal pivotal axis to swing said arm vertically to adjust said drilling tool into different parallel positions, said arm being swingable horizontally to adjust said drilling tool into different parallel positions at opposite sides of said truck, and driving connections between said motor and said drilling tool.
- 70 24. In a drilling apparatus, a portable support, a motor thereon, an elongated supporting arm pivotally mounted at its rear end on said support for swinging movement about vertical and horizontal axes, said arm being swingable horizontally and vertically about said axes, mechanism driven by said motor for swinging said arm about its horizontal axis to move said drilling tool into different positions about said longitudinal axis, and driving connections between said motor and said drilling tool.
- 10 25. In a drilling apparatus, a wheeled truck, a motor thereon for driving the truck wheels to propel the apparatus along the trackway, an elongated supporting arm pivotally mounted at its rear end on said truck for swinging movement about angularly disposed axes, said arm being adjustable vertically and horizontally about said axes, mechanism driven by said motor for swinging said arm about one of its pivotal axes aforesaid, a drilling tool adjustably mounted on the outer extremity of said arm, mechanism for rotating said arm about its longitudinal axis to move said drilling tool into different positions about said longitudinal axis, and driving connections between said motor and said drilling tool.
- 15 26. In a drilling apparatus, a wheeled truck, a motor thereon for driving the truck wheels to propel the apparatus along a trackway, an elongated supporting arm pivotally mounted at its rear end on said truck for swinging movement about angularly disposed axes including a horizontal pivotal axis, a drilling tool adjustably mounted on the outer extremity of said arm, mechanism for rotating said arm about its longitudinal axis to move said drilling tool into different positions about said longitudinal axis, mechanism driven by said motor for swinging said arm about its horizontal pivotal axis to swing the same vertically to position said drilling tool into different parallel positions, said arm being swingable horizontally to position said drilling tool into different parallel positions at opposite sides of said truck, and driving connections between said motor and said drilling tool.
- 20 27. In a drilling apparatus, a portable support, an elongated supporting arm pivotally mounted on said support for swinging movement about a horizontal pivot axis, a drilling tool adjustably mounted on the outer extremity of said arm, a motor, and mechanism driven by said motor for swinging said arm upwardly and downwardly about its pivot to position said drilling tool into different parallel planes and including a driving element arranged with its axis aligned with the arm pivot axis.
- 25 28. In a drilling apparatus, a portable support, an elongated supporting structure adjustably mounted on said support and extending a substantial distance in advance of said support, a drilling tool adjustably mounted on the outer extremity of said supporting structure, said supporting structure being adjustable to position said drilling tool in a plurality of relatively high and relatively low parallel planes and into positions at either side of said support, a motor on said support relative to which said supporting structure is adjustable as aforesaid, mechanism driven by said motor for driving the drilling tool and including a driving element arranged with its axis extending longitudinally of said supporting structure, and mechanism driven by said motor

through said driving element for adjusting said supporting structure relative to said support.

29. In a drilling apparatus, a portable support, an elongated supporting structure adjustably mounted on said support and extending a substantial distance in advance of said support, a drilling tool adjustably mounted on the outer extremity of said supporting structure, said supporting structure being adjustable to position said drilling tool in a plurality of relatively high and relatively low parallel planes and into positions at either side of said support, a motor, mechanism driven by said motor for driving the drilling tool, mechanism driven by said motor for adjusting said supporting structure relative to said support, and mechanism driven by said motor for propelling the apparatus.

30. In a drilling apparatus, a portable support, a turntable thereon, means for locking said turntable in its different positions of adjustment relative to said support, an elongated supporting structure adjustably mounted at its rear end on said turntable for adjustment into different lateral positions and into different elevated positions relative thereto, a drilling tool adjustably mounted on the outer extremity of said supporting structure, said tool being adjustable with said supporting structure into different parallel elevated positions and into different parallel lateral positions relative to said support, and means for driving the drilling tool and effecting certain adjustments of said supporting structure relative to said support including a motor relative to which said supporting structure is adjustable, and driving elements driven by said motor and including a driving element arranged with its axis extending longitudinally of said supporting structure and through which said adjusting means is driven.

40 31. In a drilling apparatus, a portable support, a turntable thereon, means for locking said turntable in its different positions of adjustment relative to said support, an elongated supporting structure adjustably mounted at its rear end on said turntable for adjustment into different lateral positions and into different elevated positions relative thereto, a drilling tool adjustably mounted on the outer extremity of said supporting structure, said tool being adjustable with said supporting structure into different parallel elevated positions and into different parallel lateral positions relative to said support, a motor for driving the drilling tool and effecting certain adjustments of said supporting structure relative to said support, and mechanism driven by said motor for propelling the apparatus.

45 32. In a drilling apparatus, a portable support, a turntable thereon, means for locking said turntable in its different positions of adjustment relative to said support, an elongated supporting structure adjustably mounted at its rear end on said turntable for adjustment into different lateral positions and into different elevated positions relative thereto, a drilling tool adjustably mounted on the outer extremity of said supporting structure, said tool being adjustable with said supporting structure into different parallel elevated positions and into different parallel lateral positions relative to said support, mechanism for turning said supporting structure about its longitudinal axis to adjust the drilling tool into different positions either below, above, or at either side of said supporting structure, and a motor for driving the drilling tool and effecting cer-

tain adjustments of said supporting structure relative to said support.

5 33. In a drilling apparatus, a portable support, a turntable thereon, means for locking said turntable in its different positions of adjustment relative to said support, an elongated supporting structure adjustably mounted at its rear end on said turntable for adjustment into different lateral positions and into different elevated positions relative thereto, a drilling tool adjustably mounted on the outer extremity of said supporting structure, said tool being adjustable with said supporting structure into different parallel elevated positions and into different parallel lateral positions relative to said support, mechanism for turning said supporting structure about its longitudinal axis to position the drilling tool into different positions either below, above, or either side of said supporting structure, a motor for driving the drilling tool and effecting certain adjustments of said supporting structure relative to said support, and mechanism driven by said motor for propelling the apparatus.

20 34. In a drilling apparatus, a portable support, a pair of independently adjustable elongated supporting structures mounted at their rear ends on the forward end of said support, said supporting structures at their rearward ends overlying said support and extending forwardly a substantial distance in advance of said support, a drilling tool supported on the outer extremity of each supporting structure in advance of said support, said supporting structures being adjustable to position said drilling tools into different relatively high parallel positions and into different relatively low parallel positions relative to said support and in different lateral positions to enable said tools to drill holes above, below and at either side of said support, a motor on said support, and driving connections between said motor and said tools.

25 35. In a drilling apparatus, a portable support, a pair of independently adjustable elongated supporting structures mounted at their rear ends on the forward end of said support, said supporting structures at their rearward ends overlying said support and extending forwardly a substantial distance in advance of said support, a drilling tool supported on the outer extremity of each supporting structure in advance of said support, said supporting structures being adjustable to position said drilling tools into different relatively high parallel positions and into different relatively low parallel positions relative to said support and in different lateral positions to enable said tools to drill holes above, below and at either side of said support, a motor on said support, driving connections between said motor and said tools, and mechanism driven by said motor for propelling said support.

30 36. In a drilling apparatus, a portable support, a pair of independently adjustable elongated supporting structures mounted at their rear ends on the forward end of said support and extending a substantial distance in advance of said support, a drilling tool supported on the outer extremity of each supporting structure, said supporting structures being adjustable to position said drilling tools into different relatively high parallel positions and into different relatively low parallel positions relative to said support and in different lateral positions to enable said tools to drill holes above, below and at either side of said support, a motor on said support, driving connections between said motor and said tools, and

mechanism driven by said motor for independently adjusting said supporting structures.

37. In a drilling apparatus, a portable support, an elongated supporting structure mounted at its rear end on the forward end of said support and extending a substantial distance in advance thereof, a drilling tool carried at the outer extremity of said supporting structure, said supporting structure being adjustable to position said tool above, below and laterally at the side of said support to position said tool into different relatively high and relatively low planes and different lateral planes, motor operated devices on said support relative to which said supporting structure is adjustable for driving said tool, and motor operated devices for adjusting said supporting structure relative to said support, said adjusting and tool driving means including a common driving element arranged on and extending longitudinally of said supporting structure.
38. In a drilling apparatus, a portable support, an elongated supporting structure mounted at its rear end on the forward end of said support and extending a substantial distance in advance thereof, a drilling tool carried at the outer extremity of said supporting structure, said supporting structure being adjustable to position said tool above, below and laterally at the side of said support to position said tool into different relatively high and relatively low planes and different lateral planes, a motor on said support relative to which said supporting structure is adjustable for driving said tool, and mechanism driven by said motor for adjusting said supporting structure relative to said support.

39. In a drilling apparatus, a portable support, a pair of independently adjustable elongated supporting structures mounted at their rear ends on the forward end of said support and extending a substantial distance in advance of said support, a drilling tool supported on the outer extremity of each supporting structure, said supporting structures being adjustable in vertical planes extending longitudinally of the apparatus to position said drilling tools into different relatively high parallel positions and into different relatively low parallel positions relative to said support and horizontally relative to said support into different lateral positions to enable said tools to drill holes in advance of said support in a direction parallel to the longitudinal axis of the apparatus, said tools being adjustable to drill holes above, below and at either side of said support, and motor operated devices including driving elements common to the drive of both tools for driving said drilling tools.
40. In a drilling apparatus, a portable support, a pair of independently adjustable elongated supporting structures mounted at their rear ends on said support at opposite sides of the latter and extending a substantial distance in advance of said support, a drilling tool supported on the outer extremity of each supporting structure, said supporting structures being adjustable in vertical planes extending longitudinally of the apparatus to position said drilling tools into different relatively high parallel positions and into different relatively low parallel positions relative to said support and into different lateral positions to enable said tools to drill holes in advance of said support in a direction parallel to the longitudinal axis of the apparatus, said tools being adjustable to drill holes above, below and at either side of said support, and motor operated devices including driving elements common to the drive of both tools for driving said drilling tools.

41. In a drilling apparatus, a portable support, a pair of independently adjustable elongated supporting structures mounted at their rear ends on the top of said support, said supporting structures overlying said support and extending forwardly a substantial distance in advance of said support, a drilling tool supported on the outer extremity of each supporting structure in advance of said support, said supporting structures being adjustable in vertical planes extending longitudinally of the apparatus to position said drilling tools into different relatively high parallel positions and into different relatively low parallel positions relative to said support and into different lateral positions to enable said tools to drill holes in advance of said support in a direction parallel to the longitudinal axis of the apparatus, said tools being adjustable to drill holes above, below and at either side of said support, and motor operated devices including driving elements common to the drive of both tools for driving said drilling tools.
42. In a drilling apparatus, a portable support, a pair of independently adjustable elongated supporting structures mounted at their rear ends on the forward end of said support and extending a substantial distance in advance of said support, said supporting structures being adjustable vertically and laterally relative to said support, a drilling tool supported on the outer extremity of each supporting structure, said supporting structures being adjustable in longitudinal planes relative to said support to position said drilling tools into different relatively high parallel positions and into different relatively low parallel positions relative to said support and into different lateral positions to enable said tools to drill holes in advance of said support in a direction parallel to the longitudinal axis of the apparatus, said tools being adjustable to drill holes above, below and at either side of said support, and motor operated devices including driving elements common to the drive of both tools for driving said drilling tools.

43. In a drilling apparatus, a portable support, a pair of independently adjustable elongated supporting structures mounted at their rear ends to swing about rectangularly related axes on the forward end of said support and extending a substantial distance in advance of said support, said supporting structures being adjustable about their axes both vertically and laterally relative to said support, a drilling tool supported on the outer extremity of each supporting structure and adjustable relative to the latter in planes parallel with the longitudinal axis of said supporting structure, said supporting structures being adjustable to position said drilling tools into different relatively high parallel positions and into different relatively low parallel positions relative to said support and into different lateral positions to enable said tools to drill holes above, below and at either side of said support, and motor operated devices including driving elements common to the drive of both tools for driving said drilling tools.

44. In a drilling apparatus, a portable support, a pair of independently adjustable elongated supporting structures mounted at their rear ends on the top of said support, said supporting structures overlying said support and extending forwardly a substantial distance in advance of said support, a drilling tool supported on the outer extremity of each supporting structure in advance of said support, said supporting structures being adjustable in vertical planes extending longitudinally of the apparatus to position said drilling tools into different relatively high parallel positions and into different relatively low parallel positions relative to said support and into different lateral positions to enable said tools to drill holes in advance of said support in a direction parallel to the longitudinal axis of the apparatus, said tools being adjustable to drill holes above, below and at either side of said support, and motor operated devices including driving elements common to the drive of both tools for driving said drilling tools.

ble to position said drilling tools into different lateral positions relative to said support, a motor carried by said support and relative to which said supporting structures are adjustable, and driving connections between said motor and said drilling tools.

45. In a drilling apparatus, a portable support, a pair of independently adjustable elongated supporting structures mounted at their rear ends on the top of said support, said supporting structures overlying said support and extending forwardly a substantial distance in advance of said support, a drilling tool mounted on the outer extremity of each supporting structure in advance of said support, said supporting structures being adjustable to position said drilling tools into different elevated positions and into different lateral positions to enable said tools to drill holes above, below and at either side of said support, a motor carried by said support and relative to which said supporting structures are adjustable, and driving connections between said motor and said drilling tools.

46. In a drilling apparatus, a portable support, a pair of independently adjustable elongated supporting structures mounted at their rear ends on the top of said support, said supporting structures overlying said support and extending forwardly a substantial distance in advance of said support, a drilling tool supported on the outer extremity of each supporting structure in advance of said support, said supporting structures being adjustable to position said drilling tools into different lateral positions relative to said support, a motor carried by said support and relative to which said supporting structures are adjustable, driving connections between said motor and said drilling tools, and devices driven by said motor for propelling the apparatus.

40 47. In a drilling apparatus, a portable support, a pair of independently adjustable elongated supporting structures mounted at their rear ends on said support and extending a substantial distance in advance of said support, a drilling tool mounted
45 on the outer extremity of each supporting structure, said supporting structures being adjustable to position said drilling tools into different elevated positions and into different lateral positions to enable said tools to drill holes above, below and at either side of said support, a motor carried by said support and relative to which said supporting structures are adjustable, driving connections between said motor and said drilling tools, and devices driven by said motor for adjusting said supporting structures relative to said support.

48. In a drilling apparatus, a portable support, a pair of independently adjustable elongated supporting structures mounted at their rear ends on the forward end of said support and extending a substantial distance in advance of said support, said supporting structures being adjustable in a vertical direction relative to said support, a drilling tool supported on the outer extremity of each supporting structure and adjustable angularly in a vertical direction relative thereto about an axis extending transversely of its supporting structure to drill holes in relatively inclined planes above and below said supporting structure, said supporting structures being adjustable to position said drilling tools into different relatively high parallel positions and into different relatively low parallel positions relative to said support and into different lateral positions to enable said tools to drill holes in planes above, below and at either

side of said support, and motor operated devices including driving elements common to the drive of both tools for driving said drilling tools.

49. In a drilling apparatus, a portable support, a pair of independently adjustable elongated supporting structures mounted at their rear ends on said support at opposite sides of the latter and extending a substantial distance in advance of said support, said supporting structures being adjustable in a vertical direction relative to said support, a drilling tool supported on the outer extremity of each supporting structure and adjustable angularly in a vertical direction relative thereto about an axis extending transversely of its supporting structure to drill holes in relatively inclined planes above and below said supporting structure, said supporting structures being adjustable to position said drilling tools into different relatively high parallel positions and into different relatively low parallel positions relative to said support and into different lateral positions to enable said tools to drill holes in planes above, below and at either side of said support, and motor operated devices including driving elements common to the drive of both tools for driving said drilling tools. 5 10 15 20 25

50. In a drilling apparatus, a portable support, a pair of independently adjustable elongated supporting structures mounted at their rear ends on said support for swinging movement about parallel axes and extending a substantial distance in advance of said support, a drilling tool supported on the outer extremity of each supporting structure and adjustable angularly in a vertical direction relative thereto in planes parallel with the longitudinal axis of its supporting structure to drill holes in relatively inclined planes above and below said supporting structure, said supporting structures being adjustable to position said drilling tools into different relatively high parallel positions and into different relatively low parallel positions relative to said support and into different lateral positions to enable said tools to drill holes in planes above, below and at either side of said support, and motor operated devices including driving elements common to the drive of both tools for driving said drilling tools.

51. In a drilling apparatus, a portable support, a pair of independently adjustable elongated supporting structures mounted at their rear ends on the forward end of said support and extending a substantial distance in advance of said support, said supporting structures being adjustable vertically and laterally relative to said support, a drilling tool supported on the outer extremity of each supporting structure and adjustable angularly in a vertical direction relative thereto in planes parallel with the longitudinal axis of its supporting structure to drill holes in relatively inclined planes above and below said supporting structure, said supporting structures being adjustable to position said drilling tools into different relatively high parallel positions and into different relatively low parallel positions relative to said support and into different lateral positions to enable said tools to drill holes in planes above, below and at either side of said support, and motor operated devices including driving elements common to the drive of both tools for driving said drilling tools.

52. In a drilling apparatus, a portable support, a pair of independently adjustable elongated supporting structures mounted at their rear ends about rectangularly related axes on the forward end of said support and extending a substantial 75

- distance in advance of said support, said supporting structures being adjustable about their axes both vertically and laterally relative to said support, a drilling tool supported on the outer extremity of each supporting structure and adjustable angularly in a vertical direction relative thereto in planes parallel with the longitudinal axis of said supporting structure to drill holes in relatively inclined planes above and below said supporting structure, said supporting structures being adjustable to position said drilling tools into different relatively high parallel positions and into different relatively low parallel positions relative to said support and into different lateral positions to enable said tools to drill holes in planes above, below and at either side of said support, and motor operated devices including driving elements common to the drive of both tools for driving said drilling tools.
53. In a drilling apparatus, a portable support, a pair of independently adjustable elongated supporting structures mounted at their rear ends on said support and adjustable in horizontal and vertical directions relative to said support, a drilling tool swivelly mounted on the outer extremity of each supporting structure, said supporting structures being adjustable as aforesaid relative to said support and said tools relative to said supporting structures to position the drill-

ing tools to drill a series of parallel holes extending in a direction longitudinally of the apparatus and at any desired position in a working face in advance of the apparatus, and motor operated means including driving elements common to the drive of both tools for driving said tools and for effecting one of the adjustments of said supporting structures relative to said support.

54. In a drilling apparatus, a portable support, a pair of independently adjustable elongated supporting structures mounted at their rear ends on said supports and adjustable in horizontal and vertical directions relative to said support, a drilling tool swivelly mounted on the outer extremity of each supporting structure about axes extending transversely of the longitudinal axes of said supporting structures, said supporting structures being adjustable as aforesaid relative to said support and said tools relative to said supporting structures to position the drilling tools to drill a series of parallel holes extending in a direction longitudinally of the apparatus and at any desired position in a working face in advance of the apparatus, and motor operated means including driving elements common to the drive of both tools for driving said tools and for effecting a certain adjustment of said supporting structures relative to said support.

MORRIS P. HOLMES.
